UNITED STATES PATENT OFFICE

DELANCEY W. DAVIS, OF WILKES-BARRE, PENNSYLVANIA

RAIL AND FLANGE OILER

Application filed February 6, 1929. Serial No. 337,921.

This invention relates to a railroad rail and wheel flange oiler unit and it is generally aimed to provide a simple, compact, durable and reliable construction which is capable of oiling both of said parts simultaneously and which is operable by passing rolling stock.

A particular object is to provide a novel construction which is fastened to the rail and so fitted and related as to be actuated either on straight runs or curves, avoids undue lateral projection and obstruction with respect to the rail and trackway, and is capable of maintaining its operative position in the event parts thereof should become detached.

Another object is to provide a new combination comprising a pump in free communication with a source of oil supply capable of filling without affecting operation, and a valve located between a discharge nozzle and the pump to prevent back flow of the oil.

A further aim is to produce a novel rail-embracing pipe section to carry the nozzle. Various additional objects and advantages will become apparent from a consideration of the description following taken in connection with accompanying drawings illustrating an operative embodiment.

30 In said drawings—

Fig. 1 is a view illustrating my invention in side elevation operatively associated with a rail and its support.

Fig. 2 is a plan view of the parts of Fig. 1.

35 Fig. 3 is a cross sectional view taken on the line 3—3 of Fig. 1, a car wheel being additionally shown.

Fig. 4 is a cross sectional view taken on the line 4—4 of Fig. 1.

40 Fig. 5 is a detail horizontal sectional view taken on line 5—5 of Fig. 1.

Fig. 6 is a detail sectional view taken on the line 6—6 of Fig. 2 to illustrate the details of the pump, and Fig. 7 is a detail,

45 partly in longitudinal section and partly in side elevation, through the check valve device employed.

In order to render the mounting and operation of the invention clear, I have shown a conventional railway rail at 10 disposed on

tie-plates 11 in turn spiked to ties 12, and a car wheel 13 to traverse the said rail 10.

Referring to the parts constituting my invention, a horizontally disposed nozzle 14 is arranged adjacent to or in contact with the wheel-flange side 15 of the rail and is provided with a multiplicity of ports or orifices 16, through which oil or other lubricant is discharged upwardly against the rail-head side of the flange 17 of said wheel 13.

The lubricant for nozzle 14 is supplied from a reservoir 18 through a delivery pipe 19 comprising straight section 20, in which a pump 21 is fastened, and end section 22. Nozzle 14 may be formed integral with the end section 22 as shown.

The reservoir 18 is a relatively long and attenuated body which partially enters the fishing space of the rail, as particularly shown in Fig. 4. This reservoir in practice may be approximately three inches in diameter and six feet long, so that it will contain a considerable supply of oil or lubricant which may be supplied through an opening covered by a filling plug 19. The reservoir 18 may be secured in place in any desired manner and, for instance, by cleats or clamps 20, which partially embrace the reservoir 18, and are secured in place by spikes 21, the latter also serving to secure adjacent tie-plates in place.

Pipe section 20 leads directly from reservoir 18 to the cylinder of the pump 21, which is designated 22'. Cylinder 22' has a removable top or closure 23 screw threaded thereto at 24. A piston 25 is operable within cylinder 22', preferably having packing rings on its periphery, as at 26. Said piston 25 is normally centrally located in the cylinder 22', as shown in Fig. 6, and is held by means of coil springs 27 located on opposite sides thereof in abutment therewith, and one abutting the base of the cylinder, and the other abutting the top 23. A piston rod 28 is screw threaded at 29 to the piston or head 25 and is slidably mounted through a central opening 30 in the top 23. A cap 31, preferably of hardened steel to resist wear, is screw threaded at 32 to the top of the rod 28 and is located exteriorly of the cylinder 100.

22'. Such cap 31 is adapted to be engaged and depressed by the wheel 13 as it traverses rail 10 so as to cause operation of the pump. The screw threads 32 permit vertical adjustment of the cap 31 so as to vary the throw of the piston 25, and such cap 31 may be fastened in its different adjusted positions by means of a binding screw or equivalent element 33 carried by the cap.

10 The cylinder 22 has integral attaching plates or flanges 34, by means of which they may be bolted, or otherwise fastened, as at 35, to the web of the rail, the pump structure accordingly partially fitting into the fishing space of the rail.

15 A series of short pipes and fittings 36, in detachable screw-threaded relation lead from the cylinder 22' to the end pipe section 22 and include a ball choke or check valve device 37 as detailed in Fig. 7. Such device 37 includes a hollow casing 38 screw threaded to the section 22 and a nipple 39 screw threaded to the casing 38 and to the series of couplings 36. Nipple 39 is normally closed by 20 a ball valve 40 which seats against the same and is urged into and normally held in closed position by means of an expansive spring 41 located within the abutment and casing 38.

25 Depression of the pump 31, in view of the fact that the lower portion of cylinder 22 is always in full or unrestricted communication with the reservoir 18, forces a quantity of oil through the connections 36 and past the check valve 40, the valve 40 acting automatically to open to permit the oil to pass it and to close automatically to prevent return of oil to the pump.

30 End pipe section 22, as best shown in Fig. 3, extends under the rail 10, between ties, and then upwardly and in combination with the fittings 36 over the base flange 42 at one side of the rail, fitting in a notch 43 thereof, and at its other end extending upwardly 35 and over the base flange 42, as at 44, thence upwardly against the web of the rail, at 45, and thence outwardly to the nozzle 14.

35 As a result of the construction described, operation of the pump 21 maintains end pipe section 22 and nozzle 14 full of oil which can not return, due to the presence of the check valve 40. As the car wheel or wheels 14 traverse the rail 10, each wheel at its periphery or tread engages the cap 31, thereby depressing it and pumping a quantity of the oil from the reservoir through pipe section 20, cylinder 22, connections 36, past valve 40, into pipe section 22 and thence into the nozzle 14, from which the oil escapes through 40 orifices 16, thereby lubricating the inner surface of the wheel flange and by contact therewith, the side of the rail head. Thus it will be seen that the pump is normally inactive and is operated by each wheel 13 which passes 45 over the same, the pump automatically being

restored to normally inactive position after each operation by the springs 27.

50 Although I have shown the invention applied to but a single rail, the same may be used on both rails and the device arranged in transverse alignment on both of the rails, or such devices may be provided at any desired interval, or intervals, along either or both rails.

55 It will be noted that the various parts constituting the invention or unit are interfitting in the fishing space of the rail and that the pipe section 22 rather closely conforms to the shape of or embraces the rail, which is important not only from the standpoint of compactness but to enable the parts to remain substantially in their normal or attached position if any of the parts should become detached. To aid in attaining this result, the lower surface of the cylinder 22 is preferably inclined as at 46 (see Fig. 3) conforming with the angle of the adjacent portion of the base flange 42 of the rail, so as to rest on such portion if flange 34 should break or bolts 35 loosen.

60 Various minor changes may be resorted to provided they fall within the spirit and scope of the invention.

I claim as my invention:

65 1. In combination with a rail, a delivery pipe section arranged to discharge lubricant adjacent the head of the rail, said section being disposed transversely under the rail, thence upwardly and over the base on both sides of the rail, a nozzle on one terminal of the pipe section and lubricant supply means connected to the other terminal of the pipe section.

70 2. A rail and wheel flange oiler comprising, in combination, a lubricant pump to be secured to the outer side of a T rail, a delivery conduit in communication with said pump formed to extend therefrom under the base of the rail, about the inner side of the base thereof to the web thereof, then upwardly 100 and outwardly to a point adjacent the outside of the head thereof, a delivery nozzle receiving from said conduit to deliver lubricant to the inner surface of the flange of a passing wheel, a piston in said pump, a piston rod 105 projecting into the path of a passing wheel tread, a lubricant reservoir and a conduit to conduct lubricant from said reservoir to said pump.

75 3. A rail and wheel flange oiler comprising, in combination, a lubricant pump to be secured to the outside of the web of a T rail, a spring returned plunger in said pump, a wheel engaging head on said plunger, means to adjust the effective length of said plunger 110 to vary the stroke of the pump, a lubricant reservoir separate from said pump, a conduit connecting said reservoir and pump inlet, a conduit leading from said pump, a check valve in said last named conduit, said outlet 115
